Attorney

UNITED STATES PATENT OFFICE.

LEO N. KENWARD, OF LAKWOOD, OHIO.

AUTOMOBILE HEADLIGHT.

Application filed May 18, 1926. Serial No. 109,918.

My present invention pertains to automobile headlights, and contemplates the provision of a headlight which while simple and inexpensive in construction and capable of adequately lighting the road in front of an automobile, is so characterized as to avert glare in front of and at the side of the line of the vertical center of the headlight.

To the attainment of the foregoing, the invention consists in the improvement as hereinafter described and definitely claimed.

In the accompanying drawings, forming part of this specification:—

Figure 1 is a longitudinal vertical central section of the headlight constituting the preferred embodiment of my invention.

Figure 2 is a front end elevation of the headlight.

As illustrated in Figure 1, my novel headlight is made up of a casing 1, closed at its back and open at its front, an incandescent electric lamp 2 arranged in the upper rear portion of the casing and carried by a socket 3 attached to the back wall of the casing, a reflector 4 disposed in the casing 1 and about the socket 3 and open at its forward end, a lens 5, and a lens holder 6, the said holder 6 being joined preferably in detachable manner to the casing 1 and being adapted to normally hold the lens 5 in the relative position illustrated, that is to say with the rear side of the lens 5 abutting against the forward end of the reflector 4 and the forward end of the casing 1 and closing the open end of the reflector.

While I show the reflector 4 as formed in one piece, I would have it understood that it is within the purview of my invention to form the reflector 4 in longitudinal sections, the longitudinal edges of the said sections being abutted and appropriately joined.

The reflector 4 is of the general configuration illustrated, and is tapered toward its rear end and is arranged in the casing 1 in a generally inclined position. The entire inner surface of the element 4 is reflective in character so as to contribute to the illuminating quality of the headlight.

As will be appreciated from Figure 1, the major portion of the forward open end of the reflector 4 is disposed in a horizontal plane below that in which the lamp 2 is located, and from this it follows that the forward upper portion of the reflector 4 will tend to cast the light rays forwardly and downwardly, and will prevent the projec-

tion of a large portion of the light rays directly forward in a horizontal plane from the lamp 2.

As will be understood by comparison of Figures 1 and 2, the forward flange 7 of the lens holder 6 is diminished in width from the upper vertical median portion of the flange to the lower vertical median portion thereof. In other words, the upper portion of the said flange 7 reaches downwardly to a point in about the same horizontal plane as the upper portion of the forward end of the reflector 4.

In the horizontal plane of the lamp 2 and extending slightly below said plane is the fully transparent portion 8 of the lens 5, the remainder of the said lens 5 being frosted or being colored and thereby rendered translucent as designated by 9 in Figure 2. It will be noted that the said frosted or colored and translucent portion 9 of the lens 5 is disposed below the fully transparent portion 8 and also at opposite sides of said portion 8, the shape of the portion 9 being preferably that of a crescent as illustrated in Figure 2, and consequently the portion 9 being of a character to retard the passage of light rays will effectively prevent glare in the line of the vertical center of the headlight and also at opposite sides of said line, and this notwithstanding the roadway in front of the headlights will be adequately illuminated.

It will be apparent from the foregoing that my novel headlight while practically advantageous as stated, is simple and inexpensive in construction and in general is well adapted to withstand the usage to which headlights are ordinarily subjected.

I have explicitly described the present and preferred embodiment of my invention in order to impart a full, clear and exact understanding of the said embodiment. I do not desire, however, to be understood as limiting myself to the structure shown and described, my invention being defined by my appended claim within the scope of which modifications may be made without departure from my invention.

Having described my invention, what I claim and desire to secure by Letters-Patent, is:—

In a headlight and in combination, a reflector closed at its rear end and open at its forward end and tapered toward said rear end and generally inclined downwardly and forwardly, a lamp in the rear end portion of

the reflector, and a lens opposed to and arranged about the forward open end of the reflector and having an upper fully transparent vertical central portion, the upper 5 part of which is in the same horizontal plane as the horizontal center of the lamp, and also having a major portion below and at opposite sides of the fully transparent portion; the said major portion being of a character 10 to retard the passage of light rays with a view to averting glare, and the combined area of the fully transparent portion and the

said major portion of the lens corresponding to the area of the forward end of the reflector, with a lens holder mounted on the 15 forward portion of the casing and having a front flange, said flange tapered in width from the upper portion of its vertical median line to the lower portion of said vertical median line and having the lower edge 20 of its upper portion flush with the forward end of the upper portion of the reflector.

In testimony whereof I affix my signature.
LEO KENWARD.
